GARMENT PROTECTOR

Clarence L. Weeks, Garyville, La.

Application January 22, 1946, Serial No. 642,738

2 Claims. (CL 36—2)

1

This invention relates to a garment protector, and more particularly to such a protector adapted to prevent damage to garments, as from the effect of rain, snow, sleet, or similar moisture.

A primary object of this invention is the provision of an improved garment protector particularly adapted for the covering of the trouser legs of an individual, particularly the lower portions thereof such as normally depend below a raincoat or similar garment.

An additional object of the invention is the provision of such a device provided with means whereby the same may be readily attached to the person of the wearer and readily detached as desired.

A further object of the invention is the provision of such a device provided with means at its lower extremity whereby the lower portion thereof may be turned up interiorly of the trouser cuffs, thus fully protecting the entire length of the trousers from all moisture as occasioned by rain or the like.

A still further object of the invention is the provision of such a device which is sturdy and durable in construction, reliable and efficient in operation, and relatively simple and inexpensive to manufacture and assemble.

Other objects will in part be obvious and in part be pointed out as the description of the invention proceeds and shown in the accompanying drawings, wherein there is shown a preferred embodiment of this inventive concept.

In the drawings:

Figure 1 is a side elevational view of one form of device embodying features of the instant invention shown as applied to the trouser leg of an individual.

Figure 2 is an enlarged fragmentary view partially in section, disclosing the method of securing the lower portion of the device to the trouser leg.

Figure 3 is a plan view of one of the clips utilized in so attaching the garment.

Figure 4 is a side elevational view of the device shown in Figure 3.

Figure 5 is an end elevational view of a further securing means for the device.

Figure 6 is a front plan view of the device shown in Figure 5.

Figure 7 is an end elevational view of a constructional detail.

Figure 8 is a front elevational view of the device shown in Figure 7.

Figure 9 is an exploded side elevational view of one portion of the device of the instant inven-

2

tion, disclosing the same before completion of assembly.

Similar reference characters refer to similar parts throughout the several views of the drawings.

As best shown in Figures 2 and 9, the device of the instant invention comprises a sheet generally indicated at 10 and constructed of any desired water repellent material adapted to encircle the trouser leg of an individual to a point above the knee, that is, covering that portion normally exposed by a raincoat or the like. In actual practice, of course, a pair of these devices are utilized, one for each trouser leg. The device 10 is constructed of a single piece of material having a raised portion 11 (see Fig. 9) on the exterior of the trouser leg and a cut-away portion 12 on the interior. The two portions are preferably comprised of an integral piece of material and are joined at their extremities in any suitable manner to provide a single water-tight seal. At the uppermost portion of the section 11 a tab 13 is secured to the material of the sheet and has secured thereto a double tape 14 provided intermediately with an adjusting buckle 15. As best shown in Figures 7 and 8, the adjusting buckle 15 is provided with double slots 16 and 17 to permit the adjustment of the strap therethrough in a conventional or known manner. The upper portion of the strap 14 is provided with a hook generally indicated at 18 and including a hook portion 19 attached to an elongated stem 20 and adapted to hook in the lowermost extremity of the trouser pocket 21 of a pair of trousers generally indicated at 22. The member 18 includes a loop 23, as best shown in Figure 6, adapted to accommodate the upper extremity of the strap 14.

Thus, it will be seen that when the sheet-like members 10 are positioned on the trousers, they may be readily suspended in position by means of the hooks 19 engaging in the lower extremities of the trouser pockets. Means are also provided, as best shown in Figure 2, for securing the lower extremity of the sheet 10, generally indicated at 25, interiorly of the trouser cuff 26 in such manner as to protect the cuff throughout its entire extent from dampness or moisture or the like. Such means take the form generally of clips indicated at 27 in Figures 3 and 4, which clips include upper portions 28 hingedly secured, as by hinge or pivot pins 29, to lower sections 30, which include extending portions 31 provided with inwardly turned lips 32, adapted to clamp upon the trouser cuffs. As best shown in Figure 4, the

lower member 30 is provided with an extending portion 33 adapted to be engaged by the extremity 34 of a spring clip member 35 secured, as by rivets 36, to the upper portion 28. Additional rivets 37 having enlarged heads 38 serve to secure the upper portion 28 of the clamp to the members 10.

From the foregoing the operation of the device should now be readily understandable. It is to be understood that the sheaths 10 are adapted to be positioned over the trouser legs, their inner extremities 25 inturned upwardly beneath the trouser cuff 26 and clipped in position to hold the inturned portion securely interiorly of the trouser cuff. The hooks 19 may then be secured in the trouser pockets and adjusted by means of the adjusting buckles 15 in such manner as to secure the devices in assembled relation with the trousers at the desired degree of tension and a raincoat donned by the individual over the entire assembly.

It will thus be seen that the devices or sheaths 10 of the instant invention effectively protect the trouser legs from moisture and complete the protection afforded by the conventional raincoat in such manner that the wearer's apparel is completely protected from the effects of rain, snow and sleet or the like.

It will also be seen that there is herein provided an improved device of the character described which accomplishes all the objects of this invention, and others, including many advantages of great practical utility and commercial importance.

As many embodiments may be made of this inventive concept, and as many modifications may be made in the embodiment hereinbefore shown

and described, it is to be understood that all matter herein is to be interpreted merely as illustrative and not in a limiting sense.

I claim:

- 5 1. In a device of the character described, a sheath adapted for the encirclement of the lower portion of a trouser leg comprised of water-repellant material, means for suspending said sheath from the trouser pocket, said last-mentioned means including a hook secured to the upper portion of said sheath, adjustable straps between said hook and said sheath, and means for securing the lower portion of said sheath interiorly of the trouser cuffs to protect the same.
- 10 2. In a device of the character described, a sheath adapted for the encirclement of the lower portion of a trouser leg comprised of water-repellant material, means for suspending said sheath from the trouser pocket, said last-mentioned means including a hook secured to the upper portion of said sheath, adjustable straps between said hook and said sheath, and means for securing the lower portion of said sheath interiorly of the trouser cuffs to protect the same, said last-mentioned means including spring clips.
